(57) **CLAIM**

The ornamental design for a control arm for a materials handling vehicle including a tiller, as shown and described.

DESCRIPTION

FIG. 1 is a left front perspective view of a control arm for a materials handling vehicle including a tiller showing our new design;

FIG. 2 is a left side elevational view thereof;

FIG. 3 is a right side elevational view thereof;

FIG. 4 is a top view thereof;

FIG. 5 is a back elevational view thereof; and,

FIG. 6 is a front elevational view thereof.

The bottom of the control arm is plain and unornamented.
